UNITED STATES PATENT OFFICE.

HENRY AUCHU, OF EMPORIUM, PENNSYLVANIA, ASSIGNOR TO KEYSTONE NATIONAL POWDER COMPANY, OF EMPORIUM, PENNSYLVANIA, A CORPORATION OF PENNSYLVANIA.

SHELL-CLOSER FOR SHELL-MAKING MACHINES.

1,127,718.

Specification of Letters Patent.

Patented Feb. 9, 1915.

Application filed September 21, 1914. Serial No. 882,632.

To all whom it may concern:

Be it known that I, HENRY AUCHU, a citizen of the United States, residing at Emporium, county of Cameron and State of Pennsylvania, have invented certain new and useful Improvements in Shell-Closers for Shell-Making Machines, of which the following is a specification.

This invention relates to shell closers for shell making machines.

My object is to provide an improved shell closer or folder for closing, and preferably forming a bead on, the end of a paper shell which is formed on a shell or tube machine of the mandrel type, particularly to provide improved shell closing means for use in connection with a tube or shell machine which forms a convolute wond tube or shell.

My improvements embody an improved folder operating in a novel manner to form a partial lateral bend or fold at one operation at the end of the shell when on the mandrel, and a closer adapted to complete the closing or folding of the shell or tube by another operation and, preferably, to punch in the center of the folded or closed end of the tube or shell and provide a circular raised crimp or bead.

Preferably, the folder which makes the single initial partial fold is a justable in relation to its operating means and the operating means are adaptable for other adjustments, whereby the folding member, which is preferably a blade, may be set to make the initial fold as narrow or as wide as desired and to time and regulate the operation of the aforesaid folding means.

The closing folder is mounted, operates, and is timed and correlated to the operating means for the initial or primary folder and to the latter so that no interference will be offered to the desired and predetermined action of the initial or primary folder in making the original partial fold, but after such fold is made, the final or closing folder will immediately act to form the second fold on the end of the tube or shell and, preferably, to press in the central part of the folded end of the shell and form a raised circular bead which will strengthen the folded end of the shell.

My invention differs from shell end closing or folding devices or machines heretofore known to the art in several particulars and mainly in the following: The folding

or closing action is composed of only two operations, *i. e.*, the initial folding single operation which forms the initial partial single fold, and, second, a final folding operation to lay a second single fold on top of the first single fold and, preferably, to punch in the two overlapped folds and form a crimp or bead. In tube or shell end folding or closing devices or mechanisms heretofore known to the art, the closing of the end of the tube or shell has been effected either by contracting the end of the shell by a cup-shaped closer and then punching in the central portion of the contracted several folds thus provided, or, the folding has been carried out by several steps of folding to provide a plurality of folds. The former operation results in the formation of a more or less imperfect and insecure closure as the folds only slightly overlap at the center of the end or barely meet, and in consequence, when the material, such as dynamite, is packed into shell, the packing pressure tends to spread open the end of the shell which interferes with the proper protection of the contained material and with keeping it in waterproof condition, a serious defect where the material is an explosive such as dynamite, and as paper tubes or shells thus formed have been heretofore commonly employed for holding sticks of dynamite, this form of fold has been unsatisfactory. On the other hand, that form of fold which is effected by rotating the shell and mandrel on their longitudinal axes step by step, and by the use of a multi-fingered or bladed folder, forming a series of folds as the shell and mandrel rotate step by step is unsatisfactory for the reasons set forth in connection with the first form of folder mentioned and constitutes a slower and more expensive manufacturing operation because of the extra time taken to carry out the step by step folding operation so that the output of shells from a machine of the step by step type is necessarily limited.

My improvements are adapted to very rapidly and securely fold or close the ends of paper tubes or shells whether such tubes or shells be formed on a mandrel in the same machine having my improvements, or, however my improvements may be applied or adapted to a tube or shell, regardless of how the latter may be made into tubular form. The initial folder of my invention

forms a single lateral fold at the end of the shell, by one operation. The width of this fold may be controlled and regulated at will according to the adjustment of this initially 5 acting folding device. Preferably, however, the fold is of a width sufficient to close the major portion of the end of the shell, well over toward the opposite side thereof. The secondary folder, by a single operation, 10 folds the remaining portion of the open end of the shell well over the initial fold in relatively widely overlapped relation thereto and then completes the closure. The completed folded end of the shell is, therefore, 15 composed, mainly, of two wide overlapped folds and secondary folds pressed down thereupon instead of being composed of a plurality of small inturned or bent ends or folds, such as result from the action of folding 20 mechanisms heretofore known to the art. In consequence, my improvements provide a folded or closed shell end which is strong, relatively rigid, waterproof, and will not spread apart even under excessive pressure 25 when the material, such as dynamite, is filled in the shell.

The drawings show, and the following description sets forth, a machine of the self-feeding blank, rotary convolute-winding 30 and shell stripping type as having my improvements applied thereto and coordinated with the operative mechanisms thereof, but I do not limit myself to the use of my improved shell closing or end folding means 35 in connection with the machine shown and described, nor even with a machine of that general type, as I am well aware that my improvements may be applied to other machines of this general type and even to machines which do not actually wind or form 40 the tube or shell from a blank. My shell or tube end closing or folding mechanism constituting the present invention may be used in connection with any means for supporting 45 a tube or shell by a mandrel in such manner that the open end of said tube or shell can be folded or closed by my improvements, and it is possible to employ my invention in connection with a mandrel from 50 which the tube could be slipped or stripped by hand operation after the end had been closed or folded by my invention.

I am also aware that my invention is susceptible to modifications and embodiments 55 in forms other than that specifically shown in the accompanying drawings and following description. The disclosure of the invention is to be considered as illustrative, rather than restrictive, of the spirit and 60 scope thereof.

In the accompanying drawings:

Figure 1 is a rear perspective showing one type of machine to which my improvements 65 may be applied; Fig. 2, a front perspective thereof, the initial folder being shown in

folding position; Fig. 3, a detail perspective of the folding mechanism constituting my invention, with the parts in substantially the same positions as shown in Fig. 2, the initial fold having been started; Fig. 4, a 70 detail of the initial folder blade when in position for forming the initial fold; Fig. 5, a detail of the cam and arm for shifting the final folder; Fig. 6, a detail section of the final folder; Fig. 7, a detail of the cams which swing the initial folders; Fig. 8, a detail end view of the folding mechanism of the present invention when in non-folding position; Fig. 9, a similar view showing the initial folder when it has completed its 75 work and is about to be retracted and the final folder in position to be pressed against the end of the shell; Fig. 10, a detail view of a shell on which the initial fold has been made by the present invention; Fig. 11, a 80 similar view showing the same shell when the secondary fold is about to be laid on top of the first fold; Fig. 12, a view showing the initial and secondary folds laid and the auxiliary folds overlapped thereon; and Fig. 13, a view of the completed closed end of the shell having the punched-in center and the raised bead.

The machine disclosed, to which my improvements may be applied, has a frame 1 95 supporting all operative parts. The blank holder is shown at 2 and the rotary mandrel at 3. A belt pulley 4 is used for driving the machine from any suitable source, gearing 5 being interposed between the 100 shaft of the belt pulley and a shaft 6 from which a cam shaft 7 is suitably driven by bevel gears 8. The cam shaft 7 controls all of the operations of the machine except the stripping of the shell from the mandrel and 105 the throwing in and out of the clutch which drives the mandrel. A cam 9 on shaft 6 operates a lever 10 pivoted at 11 to a bracket 12 and connected by a link or pitman 13 to the shell stripper 14, the latter sliding on a 110 suitable guide 15. The cam is so timed that the stripper 14 remains idle until the mandrel 3 has rolled the paper blank 16 into tubular form and the shell closing means have operated to completely finish the closing 115 operation by the improved mechanisms constituting the present invention. Thereupon, the cam acts with a quick throw to strip or eject the shell from the mandrel 3 and is thereafter quickly retracted so that 120 the mandrel may catch a succeeding paper blank 16 and form it into a shell. The normal position of the stripper 14 is shown in Fig. 1. There is also carried by the shaft 6 a cam 17 which retracts, at intervals a spring-actuated lever 18 pivoted intermediate its ends to the top or table of frame 1 and carrying a yoke on its upper end which is received in the groove of a clutch member 19 splined loosely and slid- 125 130 135

ably on the shaft 20 which drives the mandrel 3. Preferably the clutch 19 is spring actuated to assist the spring of the lever 18 in throwing it into engagement with the driving clutch section 21 which is loose and rotatable on the shaft or spindle 20 and is driven by a sprocket chain 22 from a large sprocket wheel 23 carried by shaft 7. The sprocket wheel 23 and clutch member 21 are constantly in motion and the clutch member 19 is engaged with the clutch member 21 for the greater portion of the time, but the cam 17 is so timed that when the blank 16 has been formed into a shell by the mandrel 3, the clutch 19 is disconnected from clutch member 21 and the mandrel then ceases rotating for a sufficient time to permit my improvements constituting the shell closing mechanism to operate and close the end of the shell and the stripper then operates to eject the shell.

The blanks 16 are fed by hand into the blank holder 2 and rest upon a lip 24 on a slidably mounted carriage 25 which is operated through a link 26, lever 27, rod 28 and cam and lever 29, the cam being carried by shaft 7. Adjustments and connections of any preferred form may be provided for the blank feeder, as the construction of this mechanism does not enter into my invention and any blank feeding means could be employed in a machine on which my shell closing means are provided.

If desired, the machine may be provided with a stamp 30 for stamping the blanks 16 with the proper printed matter. This stamp may be operated from shaft 7 by a cam 31 on said shaft, such cam being timed to stamp each blank once.

To hold the blank 16 after it has been gripped by the mandrel and to insure it being tightly wound on the mandrel in the formation of the shell, there may be employed a shell clamp 32 having any desired adjustments consisting of a concaved plate extending lengthwise parallel to the mandrel 3. This plate is carried by a slidable bar 33 and operated by a lever or rocker cooperating with a cam 34 on shaft 7, the timing being such that the clamp will be held against the blank while the shell is being formed and afterward while my shell closing mechanism closes the end of the shell, the plate 32 being thereafter released and pulled by the actuating spring employed out of engagement with the finished shell so that the stripper 14 may eject the shell from the mandrel 3.

I have sufficiently shown and described one type of shell or tube machine with which my invention can be used, but its use is not restricted to this particular type of machine, as hereinbefore pointed out, and its relationship thereto is set forth con-

formably to the provisions of the statute and such machine forms no part of my invention and may be changed or modified.

My invention embodies a primary or initial folder and the improvements embodied therein, a secondary or final folder, and improvements embodied therein, and operating means adapted to cause the initial folder to make the single initial fold and to thereupon operate the secondary or final folder to finish the closing operation. Operating means for these purposes may be varied, but such means are, in the embodiment of the invention herein set forth, operated from the shaft 7 and consists of cams 37 and 38 and a cam 39 on the shaft 6.

Referring first to the initially acting folder, this has a lever 35 which is pivoted on a bolt 40 that passes through one of a series of holes 41 in a bracket 42 which is secured to the table or frame 1. The holes 41 permit the pivotal point of the lever or arm 35 being shifted to thereby regulate the play of said lever. Carried by the lower part of the lever 35 is an adjustable piece 43, such adjustment being effected by a slot 44 in the piece 43 and a series of openings 45 in the lever 35, together with a bolt 46 passing through the slot and one of the holes, whereby the piece 43 may be extended lengthwise of the lever or swung to one side or the other and clamped by the bolt 46 to regulate the co-operation of the piece 43 with the cam 38. The cam 38 is of elongated form and adjustably connected to the inner face of the cam 37 by a bolt 47 which passes through one of a plurality of holes 48 in the cam 37. The cam 38 is arranged so that it will be adapted to engage the end 49 of the piece 43. By setting the piece 43 to different positions, the extent of co-operation of said point 49 with the cam 38 may be regulated and such regulation may be carried further by adjusting the cam 38 in relation to the cam 37. Still further adjustment is provided by the holes 41 and the bolt 40. Folder 50 is a flat blade of sufficient rigidity which has a rounded tip 51 and whose flat opposite faces taper wedge-like to the tip 51. In the folder 50 and the lever 35 there are provided slots 52, 53, through which passes a clamp bolt 54. Means are thus provided whereby the folder blade 50 may be bodily shifted in the direction of its own length or transversely thereto or moved angularly in relation to the lever 35, thus affording all possible and needed adjustments so that the folder 50 may operate as far across the end of the mandrel 3 as may be desired to form an initial fold 55 of any desired width. Preferably, the fold 55 is made sufficiently wide so that it closes the major portion of the end of the previously formed tube or shell 56 and in this folding operation, the wedge and rounded form of the folder 50 tends to press the fold 55 somewhat in-

wardly against the concaved end of the mandrel 3. The operation of the folder to produce the fold 55 is brought about by the engagement of the cam 38 with the end 49, and this engagement remains for a sufficient length of time to complete the single or initial fold, but the operation is a relatively quick one. While the fold 55 is being formed, the mandrel 3 is stationary, because at that time the cam 17 has operated the lever 18 to disengage the clutch sections 19 and 21, and while the clutch section 21 continues to rotate, such rotation is idle. The initial fold having been completed, the point 49, by the continued rotation of shaft 7, disengages from the cam 38 and thereupon a retracting spring 57 withdraws the lever 35 and the folder 50 laterally in relation to the shell 56 and clear thereof. If desired, a buffer 58 may be provided, against which the lever 35 will strike when it is retracted.

The arm 36 of the secondary or final folder is rotarily and loosely mounted on a slidably mounted rod or shaft 59, being arranged between a fixed collar 60 and a nut 61 carried by said shaft, said parts holding the arm 36 against movement lengthwise of the shaft 59, but permitting it to be rocked on said shaft. Such rocking action is controlled by a coil spring 62 and a crank or arm 63, the latter being held by a set screw 64 which, when loosened, permits any desired rocking or rotating of the crank 63 for purposes of regulation of the action of the folder. The crank or arm 63 co-operates with the periphery of the cam 37 and is held against said cam by the spring 62. Consequently, when the crank 63 arrives at the fall of the cam, the spring 62 quickly jerks the shell closing cup 65 out of alignment with the mandrel 3 so that there is no obstruction offered to the ejection of the finished shell by the stripper 14 which then acts. The final folder and crimper 66 is shown in detail in Fig. 6 and consists of the cup 65, a stem and center punch 66 secured to arm 36 by set screw 67 and a coil spring 68 which surrounds the stem 66 and tends to urge the cup 65 outwardly in relation to the free end of the punch or stem 66. Such action is, however, arrested by a pin 69 which permits cup 65 to slide inwardly on the stem 66 when the cup is applied to the partially folded end 55 of the shell 56. The cup 65 folds in the remaining portion 55^a of the end of the shell, causing it to overlap the fold 55. The cup 65 on further movement, strikes the end of the mandrel 3 and its arrest causes the stem and punch 66 to continue its advance and push in the center of the folded end, thereby also forming the circular bead 55^b so that the completed closure appears as shown in Fig. 13.

The shaft 59 is slidably mounted in suitable bearings 70 on the table of the frame

and said shaft and the folder arm 36 are normally disposed in retracted position by a spring 71 which surrounds the shaft 59 between one of the bearings 70 and an adjustable collar 72 on shaft 59, whereby the tension of spring 71 may be regulated. The length of the crank arm 63 permits said crank to remain in engagement with the cam in whatever position the folder arm 36 may be disposed, that is, either retracted by the spring 71 or when drawn toward the end of the shell. The shaft 59 is provided with an arm 73 (Fig. 5) which co-operates with the cam 39 on the shaft 6, the formation of the cam being such that the final folder will be operated against the action of spring 71 after the initial fold 55 has been made by the folder 50 and while the crank 63 remains on the highest part of the cam 37, and immediately the cup 65 and punch 66 have accomplished the final folding and bead-forming or crimping operation, the crank 63 passes off the cam and the final folder is then jerked by the spring 62 out of alignment with the shell and the arm 73 then leaves the highest point of cam 39 and the shaft 59 is shifted by spring 71 to dispose the final folder in normal position.

The general operation is as follows: The blank 16 fed downward to the mandrel 3, which thereupon grips and winds it while the clamp 32 is bearing against the paper. The clutches 19, 21 are then disengaged by the action of cam 17 on lever 18, whereupon the mandrel ceases rotating. Immediately thereafter, the rotation of shaft 7 brings the cam 38 into engagement with the point 49 of folder lever 35 and causes the folder 50 to form the initial fold 55. The point 49 then disengages cam 38 and the spring 57 quickly retracts the initial folder. The crank 63 still remaining in engagement with the dwell of the cam 37, the rotation of shaft 6 brings the arm 73 to near the highest point of cam 39, thereby shifting the folder arm 36 and causing the cup 65 to press against the partially folded end of the shell and thus form the secondary or outer fold 55^a. The arrest of the cup 65 by the end of the mandrel 3, causes the punch 66 to advance and force in the center of the shell and form the bead or crimp 55^b. Immediately this operation has been accomplished, the crank 63 passes off the dwell of cam 37, and the spring 62 then draws the final folder out of axial alignment with the end of the shell, but just before this operation, the arm 73 passes off the high point of cam 39 and the spring 71 then restores the folder arm 36 to normal position. On restoration of the final folder, the cam 9 through the lever 10 and link or pitman 13, shifts the stripper 14 and strips or ejects the shell from the mandrel. The stripper 14 is then returned to normal position by further revolution of

cam 9 and the cam 17 releases the lever 18, whereupon the spring 20 reengages the clutch sections 19 and 21. The mandrel 3 then rotates and the sequence of operations 5 is repeated by a fresh blank being gripped by the mandrel and formed into a tube or shell, the primary and secondary folds and the bead being formed on the end of the completed shell and the complete shell 10 ejected.

The operation of the mandrel and folder 50 is so timed that the final longitudinal edge of the blank from which the tube is formed is in position to be struck by the 15 folder 50 when it makes the primary or initial fold, and consequently, the final or secondary folds 53^a by being laid on top of the initial fold, prevent any opening, gapping or bulging of the final edge of the paper 20 formed into the primary or initial fold.

Having thus described my invention, what I claim as new and desire to secure by Letters Patent, is:—

1. In a shell closer, the combination with 25 a mandrel adapted to support a shell, of means movable laterally in relation to the mandrel adapted for forming at a single operation a single, initial or primary fold crosswise of the end of a shell supported 30 by said mandrel, and means movable longitudinally of the mandrel toward the end thereof adapted to form a second fold on top of the initial fold aforesaid.

2. In a shell closer, the combination with 35 a mandrel adapted to support a shell, of means movable laterally in relation to the mandrel adapted for forming at a single operation a single, initial or primary fold crosswise of the end of a shell supported by 40 said mandrel, and means movable longitudinally of the mandrel toward the end thereof adapted to form a second fold on top of the initial fold aforesaid and to completely close and form a bead on the shell end at a 45 single operation.

3. In a shell closer, the combination with 50 a mandrel adapted to support a shell, of means movable laterally in relation to the mandrel adapted for forming at a single operation a single, initial or primary fold crosswise of the end of a shell supported by 55 said mandrel, and a final folder and closer comprising a center punch, and a closing cup arranged and adapted to operate against the end of the shell after it has been partially folded by the initial folder.

4. In a shell closer, the combination with 60 a mandrel adapted to support a shell, of shell folding and closing means adapted to 65 initiate and complete the closure by two successive operations, comprising means adapted to first form a single primary fold made inwardly from one side of the shell and other means then acting to fold the opposite 75 side of the shell end on top of the initial fold

and to press in the center and "bead" the edge of the shell end.

5. In a shell closer, the combination with 70 a mandrel adapted to support a shell with the end of the latter projecting beyond the end of the mandrel, of a single folder blade, means for moving said blade inwardly and crosswise of the shell end, to form a single initially-laid primary fold extending from the outer edge of the shell crosswise thereof, 75 and a final folder and bead former, acting after the withdrawal of the folder blade, adapted to lay a second fold on the first fold and to bead or crimp the folded shell end against the end of the mandrel.

6. In a shell closer, the combination with 80 a mandrel adapted to support a shell in a stationary condition, of a single folder blade, means for moving said blade inwardly and crosswise of the shell end while the shell 85 is stationary, to form a single initially-laid primary fold extending from the outer edge of the shell crosswise thereof, and a final folder and bead-former adapted to act when the shell is stationary, embodying a cup 90 adapted to operate against the end of the shell and to fold inwardly the remaining part of the shell end in overlapped relation to the initial fold, and a punch adapted to press in the center of the overlapped folds. 95

7. In a shell closer, the combination with 100 a shell-holding mandrel, of means adapted to form an initial fold on a shell held by said mandrel, a pivoted shell closer adapted to swing in a plane crosswise in relation to the longitudinal axis of the mandrel, and also mounted for bodily shifting in the direction of the length of the mandrel, and means for imparting the foregoing movements to said shell closer to cause final closing of the shell 105 after the initial folder has withdrawn.

8. In a shell closer, the combination with 110 a mandrel, of an initial folder mounted to move in general crosswise or transverse relation to the mandrel to form the initial fold 115 on the shell, a final closer mounted to move in general crosswise or transverse relation to the mandrel for positioning said final closer, and means common to the said initial folder and final closer adapted for imparting the 120 aforesaid movements thereto.

9. In a shell closer, the combination with 125 a mandrel, of an initial folder mounted to move in general crosswise or transverse relation to the mandrel to form the initial fold 120 on the shell, a final closer mounted to move in general crosswise or transverse relation to the mandrel for positioning said final closer, means common to said initial folder and final closer adapted for imparting the 130 aforesaid movements thereto, retracting springs for said folder and closer, and means adapted to move the final closer in the direction of the length of the mandrel when it has been positioned in line therewith, to 135

thereby perform the final closing operation on a shell held by the mandrel.

10. In a shell closer, the combination with a mandrel, of an initial folder mounted to move in general crosswise or transverse relation to the mandrel to form the initial fold on the shell, a retracting spring for said folder, a final closer mounted to move in general crosswise or transverse relation to the mandrel for positioning said final closer in line with the end of the mandrel, a cam shaft, cam means carried by said shaft and coöperating with the initial folder and final closer to move them as aforesaid, said 15 cam means being arranged and timed to operate the initial folder and to release it for retraction by its spring prior to the release of the final closer, spring means for retracting the final closer, and means coöperating with the final closer adapted to move it endwise in relation to the mandrel, said means being timed to cause said movement after the initial folder has been retracted.

11. In a shell closer, the combination with 25 a spring-retracted initial folder and a spring-retracted final closer, respectively adapted to initiate and complete the folding of a shell end, of a cam coöperating with the final closer, and a secondary cam adjustably 30 carried by the main cam aforesaid and adapted to coöperate with the initial folder, whereby the timing of operation of said initial folder and final closer may be regulated.

12. In a shell closer, the combination with 35 a mandrel, of a closer mounted to move in general transverse relation to the mandrel and also in general endwise relation thereto, a cam adapted for moving the closer in general transverse relation to the mandrel and 40 coöperating with said closer when said closer is bodily shifted, and means for bodily shifting said closer while engaged with the cam.

13. In a shell closer, the combination with a mandrel, of an initial folder mounted to

move in general transverse relation to the 45 mandrel, a spring for retracting said initial folder, a final closer mounted to move in general transverse relation to the mandrel and also mounted for bodily movement in the direction of the length of the mandrel, 50 a spring for retracting said final closer, a main cam coöperating with the final closer to move it in general transverse relation to the mandrel, said final closer being arranged for adjustable coöperation with said cam, a 55 secondary cam adjustably carried by the main cam and adapted for coöperation with the initial folder, and means for moving the final closer bodily in the direction of the length of the mandrel while said final closer 60 is engaged with the main cam, said initial folder and final closer being arranged so that the former will make the initial fold on a shell held by the mandrel and will be 65 retracted to permit the final closer to be advanced in the direction of the length of the mandrel to form the final closure of the shell.

14. In a shell closer, the combination with a mandrel adapted to wind a shell from a 70 blank, of a folder movable crosswise in relation to the mandrel and arranged and adapted in relation to the mandrel for forming at a single operation a single, initial or primary fold crosswise of the end of a shell 75 wound on the mandrel and for acting on the final or outermost edge of the blank from which the shell is wound, and means for forming a second fold on top of the initial fold whereby the initial fold is prevented 80 from opening, gapping, or bulging after the shell is completed.

In testimony whereof, I hereunto affix my signature in presence of two witnesses.

HENRY AUCHU.
